DEVICE FOR REMOVING THE HEADS OF
GOLF CLUBS

William L. Wettlaufer, Buffalo, N. Y.

Application July 6, 1937, Serial No. 152,047

3 Claims. (Cl. 29—85)

This invention relates to a device which, although available for other purposes, is characterized by features which adapt it particularly to the removing of the heads of golf clubs from their shafts.

One object of the invention is to provide a device which may be manipulated with facility and without the aid of tools.

A further object is to provide a device which is so designed that marring of or injury to the parts of the club is avoided.

A still further object is to provide a novel design and arrangement of the parts of the device, whereby simplicity and economy in construction are obtained.

The invention is illustrated in the accompanying drawing in which:

Figure 1 is a perspective view showing the device applied to a golf club preparatory to the removal of the head of the latter.

Figure 2 is a top view of the device, the parts being shown in the positions to which they are adjusted to receive the club.

Figure 3 is a longitudinal section taken along line 3—3 of Figure 2.

Figure 4 is a transverse section taken along line 4—4 of Figure 2.

Figures 5 and 6 are similar sections taken along lines 5—5 and 6—6, respectively, of Figure 3.

Figure 7 is a view similar to Figure 6 showing a modified form of washer.

Figure 8 is a detail section and is taken along line 8—8 of Figure 7.

The device is illustrated, by way of example, in connection with a golf club 10 of conventional design, the head and shaft of the said club being indicated at 11 and 12, respectively, and being secured together by a screw 13, the end of the said shaft being slightly tapered in accordance with standard practice and being forced into a similarly shaped socket in the club head as the said screw is tightened.

As illustrated, the device includes a sleeve-like body 14 which is formed with a longitudinally extending slot 15, the said slot being of a width which is greater than the diameter of the shaft 12. At one end the body 14 is threaded as at 16 while at the opposite end it is formed to provide an extension 17 which is welded or otherwise secured to a plate 18. The said plate carries posts 19 and 20, the latter providing a pivotal mounting for a plate 21 which carries a saddle 22 while the former co-operates with an arcuate slot 23 formed in the free end of the plate 21. The threaded ends of the posts 19

and 20 carry wing nuts 24 which may be adjusted to move the plate 21 toward the plate 18, a spring 20a which is arranged on the post 20 between the said plates causing them to separate when the said wing nuts are loosened.

The threaded end 16 of the body 14 carries a nut 25 which is provided with a handle 25a and which is formed with a slot 26 of substantially the same width as the slot 15. The nut 25 co-operates with a washer 27 which, as illustrated in Figure 6, consists of companion sections 28 and 29. The said sections are formed to provide a central opening 31 and are connected by a link 30. They are held loosely against the shaft 12 by a latch 32 which is connected by 15 a spring 33 to the washer section 29 and which is formed or provided with teeth 34 which are engageable with a pin 35 carried by the washer section 28. The latch 32 when released permits the free ends of the sections 28 and 29 to spread 20 far enough apart to enable the shaft to enter or be withdrawn from the opening 31.

In the use of the device the washer 27 is arranged upon the shaft 12 against the terminal portion of the shank of the club head and the other parts are adjusted as shown in Figure 2, the plate 21 being positioned at right angles to the plate 18 while the nut 25 occupies a position in which the slot 26 registers with the slot 15. The body 14 of the device is arranged upon the 30 said shaft so that the nut 25 is located against or in close proximity to the washer 27. When the parts are arranged as described the plate 21 is moved to the position shown in Figure 1, in which position the saddle 22 is located over the shaft. 35 The wing nuts 24 are then tightened to cause the shaft to be engaged firmly between the saddle 22 and the body extension 17. Thereafter the nut 25 is rotated in a direction which will cause it to engage the washer 27 and move the latter axially along the shaft toward the club head, it being understood, of course, that prior to such operation the screw 13 is removed. As the washer 27 is moved along the shaft 12 in the manner described its movement is transmitted to the club head to effect the partial withdrawal of the end of the shaft from its socket, a slight movement of the club head being sufficient to loosen it to such an extent that its complete removal may be easily effected. Upon completion of the operations described the device may be readily removed by first loosening the wing nuts 24 and then slipping the device off the end of the shaft from which the club head has been removed, it being understood that, if desired, the 50 55

device may be removed by moving the plate and nut 21 and 25, respectively, to the positions shown in Figure 2 to enable the shaft 12 to be lifted out of the body 14. The washer 27 in such case is then removed by releasing the latch 32 so that the sections 28 and 29 may be spread far enough to enable the shaft to be withdrawn from the opening 31.

A modified form of washer is illustrated in Figures 7 and 8. In this embodiment the washer which is indicated at 36 consists of companion sections 37 and 38 which are connected together by a link 39. The said sections may be latched upon the shaft by a yoke 40 which is pivotally connected to the section 37. The free end of the said yoke carries a threaded element 41. The inner end of the latter is adapted to enter a recess 42 when the yoke is positioned over a reduced extension 43 which is provided upon the section 38. It will be apparent that the element 41, when the yoke 40 occupies the position shown in Figure 7, may be adjusted to cause the sections 37 and 38 to lightly engage the shaft 12. When it is desired to remove the washer 36 it may be slipped off the end of the shaft (assuming the club head to be removed) or the sections 37 and 38 may be separated to enable withdrawal of the shaft between them by first unscrewing the element 41 far enough to permit the yoke to be pivoted clear of the extension 43.

I claim as my invention:

1. A device for removing the head of a golf club including a barrel which is threaded at one end and which is formed with a longitudinally extending channel for accommodating the shaft of said club, a bar fixed to the other end of said barrel, a second bar which is pivotally mounted on said first mentioned bar and which is movable to one position in which it extends across said channel and to a second position in which it extends alongside said channel, means for moving said second bar toward said first mentioned bar when the former is in said first position, whereby to secure said shaft to said barrel and an element which is screwed upon the threaded end of said barrel and which is adjustable when said shaft is secured in the manner described to force said head off the end of said shaft, said element having a slot which may be aligned with the channel in said barrel.

2. A device for removing the head of a golf club including a barrel which is threaded at one end and which is formed with a longitudinally extending channel for accommodating the shaft of said club, a bar fixed to the other end of said barrel, a second bar which is pivotally mounted on said first mentioned bar and which is movable to one position in which it extends across said channel and to a second position in which it extends alongside said channel, means for moving said second bar toward said first mentioned bar when the former is in said first position, whereby to secure said shaft to said barrel, a nut which is screwed upon the threaded end of said barrel and a washer which fits over said shaft in the vicinity of said head and which is adjustable to the size of said shaft, said nut having a slot which may be aligned with the channel in said barrel and being adjustable when said shaft is secured in the manner described to move said washer along said shaft to carry said head with it.

3. A device for removing the head of a golf club including a barrel which is threaded at one end and which is formed with a longitudinally extending channel for accommodating the shaft of said club, a bar fixed to the other end of said barrel, a bolt carried by said bar at each side of said channel, a second bar which is pivotally mounted on one of said bolts and which is movable to one position in which it extends across said channel and to a second position in which it extends alongside said channel, said second bar being formed with a slot which the other of said bolts enters when it is moved to said first position, nuts carried by said bolts which are adjustable to move said second bar toward said first mentioned bar when the former is in said first position, whereby to secure said shaft to said barrel, an element which is screwed upon the threaded end of said barrel and a washer which fits over said shaft in the vicinity of said head and which is adjustable to the size of said shaft, said element having a slot which may be aligned with the channel in said barrel and being adjustable when said shaft is secured in the manner described to move said washer along said shaft to carry said head with it.

WILLIAM L. WETTLAUFER. 50
